CARBURETOR MIXTURE CONTROL

Brooks Walker, 1280 Columbus Ave., San Francisco, Calif., and Frank W. Kertell, Oakland, Calif.; said Kertell assignor to said Walker

Filed Aug. 27, 1962, Ser. No. 219,476

9 Claims. (Cl. 123—119)

This invention pertains to a mixture control for a carburetor, particularly when the idle air bypasses the main throttle butterfly.

On a normal carburetor the idle air passes by the main butterfly throttle and is choked by the offset butterfly choke in the air stream before the air reaches the throttle butterfly to effectively choke the air for idle or for limited power with the throttle partially open. In an anti-smog type carburetor where the fuel free air bypasses the main throttle the normal choke valve does not effect a choke on the idle air which bypasses the main throttle butterfly. Such a carburetor is shown in Hall, U.S. Patent No. 2,809,623. The choking of the fuel free air for idle is accomplished in this invention in one of three ways, (1) taking the fuel free air from between the choke butterfly and the carburetor venturi so the main choke valve chokes the air that is bypassing the throttle butterfly; (2) having a secondary small choke butterfly operated by the same shaft that operates the main choke valve the secondary small choke in the passage for the idle air that bypasses the main throttle butterfly, the main choke butterfly shaft and secondary small choke shaft being essentially in line with each other; (3) a secondary small choke valve in the path of the idle air that is close to the idle air inlet below the main throttle butterfly and the small choke operated by a linkage to the main carburetor choke which is remote from the small choke. If the idle air is not choked on a cold start the engine will not start as well if the idle air that bypasses the main throttle butterfly is choked. Having the same automatic mechanism choke the idle air that bypasses the main throttle butterfly simplifies the construction over having separate automatic choke means for this idle air.

Another feature is to take the idle air from the crank case breathing and clean the excess through the main engine air cleaner.

Other features of the invention are more particularly pointed out in the accompanying specification and claims.

We have illustrated our invention by way of example in the attached drawings in which:

FIG. 1 is an elevation view partly cut away showing one form of the invention.

FIG. 2 is a side elevation partly cut away of a portion of a carburetor embodying another form of this invention.

FIG. 3 is a side elevation of a portion of an engine and carburetor partly cut away showing a third form of this invention.

FIG. 4 is a side elevation partly cut away of a further form of the invention.

In all figures like numerals of reference refer to corresponding parts.

In FIG. 1 we have shown an engine 10, a carburetor 11, a venturi 12, a main choke valve 13, a choke shaft 14, an automatic bimetal choke device 15 (not shown in detail but illustrated in Glenn's New Auto Repair Manual, page 237, paragraph 3-51, 1961 edition). Heat for the automatic choke passes through tube 16 from pick-up 17 in exhaust manifold 18. The main air for carburetor 11 comes through air cleaner 19. Crank case breathing goes through oil filler neck 21, oil filler cap 22, tube 23 to the air cleaner 19. Idle air enters through tube 24 past idle choke valve 25 through tube 26 to heater 27 in exhaust manifold 28, such as is used on each

2

side of a V-type motor. Idle air then passes through tube 29, regulator valve 30 with screw adjustment 31 to idle air orifice 32. Idle fuel enters passage 33 in the usual manner from the float bowl of carburetor 11 and is controlled by solenoid valve 35 to cut off the idle fuel on high speed decelerations and turn on the idle fuel, by means well known in the anti-smog art. When the engine is cold automatic choke mechanism 15 moves choke 13 to the choked position and a connection to choke 25 through shaft 14 also chokes the idle air passing through tubes 24, 26, 27, 29, valve 30, orifice 32, so that the one automatic choke mechanism 15 operates choke valve 13 and choke 25 on the same shaft 14. Adjustment for idle air is achieved by screw 31 in idle air valve 30. Main throttle valve 40 is essentially closed at deceleration and idle operations.

In FIG. 2 the idle air is taken through port 41 below choke 13 and above venturi 12 through tube 42, heater 27 (if necessary the idle air to heat), line 29, idle air adjustment valve 30 and through orifice 32. Orifice 32 may be below idle fuel inlet 34 for improved mixing with idle air through port 32 while idling with main throttle valve 40 substantially closed to prevent fuel from the main jets (not shown) in the venturi 12 from entering the engine while decelerating at high speeds with idle fuel shut off by solenoid 35 for improved anti-smog operation.

In FIG. 3 idle air comes from crank case ventilator pipe 21 and the excess desired for idle air comes from pipe 23 which is cleaned by air cleaner 19. Such idle air passes through tube 45, heater 46 in exhaust manifold 47 (if heated idle air is desirable), through tube 48 to idle air valve 30 with adjustment screw 31 to idle air choke valve 49. Choke butterfly 50 is connected to main choke 13 by crank 52 (on main choke shaft 14), link 51 and arm 53 on the shaft that supports small choke 50 so that the automatic choke mechanism 15 that operates choke 13 will simultaneously operate small choke 50 in the idle air path.

The idle air in these inventions uses some of the crank case breathing. The idle air is also cleaned by the main carburetor air cleaner 19 so that all of the crank case breathing is entered into the engine induction system for better combustion of the smog-producing components of the crank case breathing fumes.

In FIG. 4 the idle air is drawn through port 65 between choke 13 and venturi 12. The idle air then passes through pipe 64, valve 62 with adjustment screw 63, tube 61 to port 60 below throttle butterfly 40. Solenoid 35 controls the flow of idle fuel through port 34 located below idle air port 60 to get good mixing of idle fuel and idle air. No heating of the idle air is provided in this invention but it can be added if desired. The choking of valve 13 by automatic choke mechanism 15 or by manual means (not shown) will also choke the idle air which bypasses the main throttle valve 40. The idle air and crank breathing are both cleaned by air cleaner 19.

We have illustrated our inventions in these various forms; however, many other variations may be possible within the scope of this invention.

To those skilled in the art to which this invention relates many changes in construction and widely differing embodiments and applications of the invention will suggest themselves without departing from the spirit and scope of the invention. The disclosures and description herein are purely illustrative and are not intended to be in any sense limiting.

We claim as our invention:

1. An engine including a carburetor, a float bowl, a throttle butterfly valve in said carburetor, a choke butterfly valve in said carburetor, an idle jet, a first passage for fuel from said float bowl to said idle jet, a sepa-

rate second passage for air from the engine side of said choke butterfly around to the engine side of said throttle butterfly, said second passage admitting the majority of air for idling when said throttle butterfly is essentially closed, air passing to said engine through said second passage being effectively choked by said choke butterfly during choke operations said idle air passage being separate from said idle fuel jet, so that the idle air passing through said idle air passage does not pass through said idle fuel jet.

2. An engine including a crank case, a carburetor, a main induction passage through said carburetor, a carburetor throat, a throttle butterfly, a main choke butterfly, said throat, throttle and choke butterfly all located in said main induction passage in said carburetor, a crank case breather connection, a separate passage around said throttle butterfly connected to said crank case breather connection, some breathing of said crank case passing through said separate passage and traveling around said throttle butterfly and into said engine on the engine side of said throttle butterfly, operating means connected to said main choke butterfly to choke said main induction passage and simultaneously effectively choke said separate passage between said crank case connection and where said separate passage connects to the engine side of said throttle butterfly.

3. A structure as described in claim 2 in which there is a choke valve in said separate passage, said choke valve being mechanically connected to the main carburetor choke so that said separate passage is choked when said main carburetor is choked.

4. An engine including a crank case, a carburetor, a main carburetor throat, a throttle butterfly, a crank case breather connection, two passages for conducting crank case breathing to said carburetor to be drawn into said engine, one path leading to the engine side of said throttle butterfly and subject to operator engine suction at the opening into said carburetor throat below said throttle butterfly, the second passage connecting said crank case breathing to the intake to the main throat of said carburetor.

5. A structure as described in claim 4 in which said engine includes an air cleaner, said air cleaner connected directly to the main throat of said carburetor, said second passage connected to said air cleaner so that if said first passage draws more flow from said crank case breather connection than the breathing of said crank case such excess will be drawn through said second passage from the outside air through said air cleaner which filters the air for the main throat to said carburetor.

6. A structure as described in claim 5 in which said main throat has a choke valve, a choke valve in said first passage, both chokes being mechanically connected to operate simultaneously.

7. An engine including a crank case, a carburetor, a carburetor throat, a throttle butterfly, a main choke butterfly, a crank case breather connection, a passage around said throttle butterfly connected to said crank case breather connection, air entering said crank case passing through said passage around said throttle butterfly and into said carburetor near said throttle butterfly on the engine side of said throttle butterfly, choke means connected to said main choke butterfly to choke said passage between said crank case connection and where said passage connects to the main carburetor throat on the engine side of said throttle butterfly, another connection from said crank case, this connection including a passage leading from the crank case to the intake to said carburetor to lead any blowby from said crank case to said carburetor when said blowby exceeds the flow through said first passage which leads around said throttle butterfly to at least one port on the engine side of said engine butterfly.

8. An internal combustion engine having a carburetor, said carburetor including a throttle valve, a choke valve, a main fuel jet, an idle-fuel jet, said idle-fuel jet admitting said fuel on the engine side of said throttle valve when said throttle valve is in the engine idle position, an idle-fuel conduit supplying fuel to said idle-fuel jet, and an idle-air passage separate from said idle fuel conduit, admitting idle-air on the engine side of said throttle valve, said separate idle-air passage picking up its air on the engine side of said choke valve so that said choke valve will choke said idle-air passage, said idle air passage being separate from said idle fuel jet, so that the idle air passing through said idle air passage does not pass through said idle fuel jet.

9. An internal combustion engine having a carburetor, fuel in said carburetor, said carburetor including a main air induction passage, a throttle valve, a main fuel jet, an idle-fuel jet, said idle-fuel jet admitting said fuel on the engine side of said throttle valve when said throttle valve is in the engine idle position, an idle-fuel conduit supplying fuel to said idle-fuel jet, an idle-air passage separate from said idle-fuel conduit, said idle-air passage admitting idle-air on the engine side of said throttle valve after bypassing said throttle valve, and choke means for simultaneously choking the air passing through said main induction passage and said separate idle-air passage, said idle air passage being separate from said idle fuel jet, so that the idle air passing through said idle air passage does not pass through said idle fuel jet.
